DRILLING BIT

Leo B. Hellman, Alvin, Tex.

Application January 31, 1941, Serial No. 376,911

1 Claim. (Cl. 255—61)

This invention relates to improvements in drilling bits and especially is concerned with a novel bit having replaceable or at least renewable cutter elements.

It is a primary object of this invention to provide a novel drilling bit useful in the boring of oil wells and the like wherein the cutter elements are renewable during use without interruption of the drilling operation to the extent required for removal of the bit.

Another object of this invention is to provide a drilling bit having renewable cutter elements which when worn can be replaced by new cutter elements with facility and ease.

An advantage of the novel drilling bit construction according to this invention over other types of drilling bits is that the cutter elements can be moved into extended cutting position by means of a loop positioned within the fluid channel passing axially through the bit, whereas replacement of cutter elements in existing types of bits has in the past required shutdown of operation of the drilling rig, withdrawal of the drill and replacement or adjustment of the bit.

Features of the novel drilling bit according to this invention are its simplicity and ruggedness of construction, the former well adapting the device to the requirements of mass production in manufacture and the latter assuring long useful life without necessity for repair.

Other objects, advantages and features of the new and improved drilling bit according to the present invention will be apparent to those skilled in this art during the course of the following description.

Regarded in certain of its broader aspects, the novel drilling bit according to the present invention comprises a body having a fluid passage extending therethrough, a rounded head on the body, slidably mounted cutters in said head extensible into cutting position, and means operable from within the fluid passage for moving the cutters into extended position.

In order to facilitate a fuller and more complete understanding of the present invention a specific embodiment thereof, herein illustrated, will be hereinafter described, it being clearly understood, however, that the illustrated embodiment, although presently preferred, is provided solely by way of example of the practice of this invention and not by way of limitation thereof except insofar as the invention is recited in the subjoined claim.

Referring then to the drawings,

Figure 1 is substantially a side elevational view

of the presently preferred embodiment of this invention with parts of the sheathing broken away to expose details of internal structure.

Fig. 2 is a bottom view of the bit shown in Fig. 1.

Fig. 3 is a horizontal sectional view of Fig. 1 taken along the line 3—3 thereof.

Fig. 4 is a vertical sectional view of Fig. 1 taken along the line 4—4 thereof.

Fig. 5 is a horizontal sectional view of Fig. 4 taken along the line 5—5 thereof, and

Fig. 6 is a horizontal sectional view of Fig. 4 taken along the line 6—6 thereof.

The illustrated preferred embodiment of the instant invention generally designated by the reference character 10 comprises a shank or body portion 11 having an opening 11a extending axially therethrough constricted at an intermediate portion 11b and further constricted at the portion 11c branching into the outlets 11d formed in the rounded end portion 11e of the bit body. A sheath member 12 surrounds the portion of the bit body located directly behind the rounded end or head 11e and serves to hold internal parts of the bit in preselected relationship as hereinafter will be made more apparent. Cutter elements 13 and 14 freely slidably mounted in openings formed in the bit head are provided with cutting end portions 13a and 14a respectively and the opposite ends of the cutter elements are formed with slots 13b and 14b respectively to facilitate connection with threaded stems 15 and 16 by means of the pins 17 and 18 held in portions of the stems and received in the slots. The stems 15 and 16 are threaded along a portion thereof as designated by the reference characters 15a and 16a and are received in axially extending openings formed in collars 19 and 20 whereby rotation of the collars is translated into

axial movement of the threaded stems, thereby causing the cutter elements 13 and 14 to move within the cutter head. The collars 19 and 20 are freely rotatably mounted within the bit body but are provided with radially extending formations 19a and 20a respectively formed on the ends thereof which abut against portions of the body to prevent axial motion of the collars. Channeled pieces 21 and 22 fitting into openings formed in the body 11 and held therein by the sleeve 12 serve further to constrict axial motion of the collars 19 and 20 while permitting free rotation of the collars.

The upper ends of the collars 19 and 20 are provided with integrally formed spur gears 23 and 24 for facilitating rotation of the collars as

hereinafter will be described. A shaft 25 carrying a second set of spur gears 27 and 28 meshing with the spur gears 23 and 24 is mounted within the body 11 extending transversely therein substantially as shown. The spur gears 27 and 23 are fixedly mounted upon the shaft 25 and rotate therewith. As will be apparent to those skilled in this art, rotation of the shaft 25 results in sliding motion of the cutter elements 13 and 14 hereinabove described.

The means for causing rotation of the shaft 25 will now be described, reference being made especially to Figs. 4, 5 and 6 wherein the reference character 29 designates a pinion gear freely rotatably mounted upon the shaft 25 and coupled by means of a ratchet clutch 30 with the spur gear 28 whereby unidirectional rotation is imparted to the spur gear by oscillation of the pinion. The elements of the ratchet clutch 30 are pressed into engagement by a spring 31 sleeved about the shaft 25 whereby the parts normally assume substantially the relationship shown in Fig. 6. A sliding bar 32 having a toothed rack end portion 32a is mounted in portions of the body 11 whereby the toothed end portion of said bar meshes with the pinion 29. The bar normally is urged by the spring 33 acting against a washer 34 which in turn presses against a pin 35 mounted in the bar to cause the bar to assume one of the extreme positions of its sliding motion which, as will be apparent to those skilled in the art from the foregoing description, reciprocation of the bar 32 will cause unidirectional rotation of the spur gear 28 and shaft 25 whereby the collars 19 and 20 will be rotated causing advancement of the stems 15 and 16 and the cutter elements 13 and 14.

A lever arm 35 fulcrumed upon a portion 36 of the body 11 is pivoted to the free end of the bar 32 and the opposite end of the lever arm is provided with a hook formation 37 whereby a loop A positioned within the fluid passage 11a can be used to reciprocate the bar 32 through operation of the lever.

In use the bit is employed as is an ordinary drilling bit and when, upon occasion, due to wear or for other reasons it is desirable to renew the cutter surfaces of the cutter elements, a loop is

positioned within the fluid passage of the bit and engaged with the hook elements on the end of the lever whereby the lever can be oscillated causing reciprocation of the pinion meshing therewith which, functioning through the unidirectional ratchet clutch, serves to rotate the spur gears and collars advancing the stems and the cutter elements, at such time as it is desirable to replace the cutter elements, the sleeve or sheath 11 is removed exposing internal parts and permitting the repairs easily to be made.

It is to be understood that this invention is capable of extended application and is not confined to the precise illustrated forms nor described construction and, therefore, such changes and modifications may be made therein as do not affect the spirit of the invention nor exceed the scope of the appended claim.

Having thus described the present invention, what it is desired to secure by Letters Patent is:

A drilling bit comprising an elongate essentially cylindrical body having a fluid passage extending axially therethrough, a rounded head on one end of said body, slidably mounted cutters in said head extensible into cutting position, means for moving the cutters into extended position comprising threaded stems attached to said cutters, collars rotatably mounted within said body in a manner precluding motion along the axis of rotation of the collars, said collars being internally threaded to receive and engage with said stems whereby rotation of the collars causes the cutters to move into extended position, means for rotating said collars comprising a shaft, a first set of spur gears on the shaft, a second set of spur gears on the collars meshing with the first set of spur gears, a pinion freely rotatably mounted on the shaft, a unidirectional ratchet clutch connecting the pinion and one of said first set of spur gears, a freely sliding rack, spring urged in one direction, meshing with said pinion, a lever arm connected to said rack for reciprocating same, and a hook element on one end of said lever within the fluid passage whereby the lever can be operated by a loop engaging said hook element.

LEO B. HELLMAN.
